Charles F. Gitschlag, Jr., Detroit, Mich., assignor to
Chrysler Corporation, Highland Park, Mich., a corpora-
tion of Delaware

Application September 2, 1955, Serial No. 37,765

Term of patent 7 years

(Cl. D14—3)

Fig. 1 is a perspective view of the rear of an automobile body with a portion of the rear bumper being broken away and showing my new design;

Fig. 2 is a vertical sectional view taken on the longitudinal center line of the body of Fig. 1;

Fig. 3 is a side elevational view of the full line portion of the automobile body shown in Fig. 1; and

Figs. 4 and 5 are transverse sectional views taken on the lines 4—4 and 5—5, respectively, of Fig. 1.

The characteristic features of my design reside in the

portions shown by means of full lines in the drawing with the front, top and side portions of the automobile being of conventional configuration.

I claim:

The ornamental design for an automobile body, sub-
stantially as shown and described.
